CLAIM

The ornamental design for a sense device, as shown and described.

DESCRIPTION

FIG. 1 is a first perspective view of a sense device showing our new design.

FIG. 2 is a second perspective view of the sense device.

FIG. 3 is a front elevational view of the sense device.

FIG. 4 is a rear elevational view of the sense device.

FIG. 5 is a right side elevational view of the sense device.

FIG. 6 is a left side elevational view of the sense device.

FIG. 7 is a top plan view of the sense device; and,

FIG. 8 is a bottom plan view of the sense device.

The sense device is intended to be used as a device for sensing movements for a security system.
